MOBILE HOME

Larry D. Moyer, Elkhart, Ind., assignor to Richardson
Homes Corporation, Elkhart, Ind.

Filed Mar. 22, 1965, Ser. No. 84,398

Term of patent 14 years

(Cl. D14—3)

The dominant features of my design reside in the portions shown in the full lines.

I claim:

The ornamental design for a mobile home, as shown and described.
